UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

PACKING MECHANISM.

1,041,808.

Specification of Letters Patent.

Patented Oct. 22, 1912.

Application filed July 15, 1910. Serial No. 572,068.

To all whom it may concern:

Be it known that I, HOWARD K. KING, a citizen of the United States, residing at Philadelphia, in the county of Philadelphia, State of Pennsylvania, have invented a new and useful Packing Mechanism, of which the following is a specification.

My invention relates to improvements in packing mechanism for folding machines.

10 The object is to provide improved means for packing sheets.

The invention comprises means for packing sheets or signatures and means whereby the mechanism may be adjusted to accommodate a wide range of sizes.

Referring to the drawings, illustrating, as an example, a preferred embodiment of my invention—Figure 1 is a side elevation of my device. Fig. 2 is an end elevation. Fig. 3 is a horizontal section on line 3—3 of Fig. 2. Fig. 4 is an end elevation showing the parts in different position. Fig. 5 is a section on line 5—5 of Fig. 4. Fig. 6 is a section on line 6—6 of Fig. 2. Fig. 7 is an elevation of a detail on an enlarged scale. Fig. 8 is a section on line 8—8 of Fig. 11. Fig. 9 is a sectional side elevation of the claw actuation mechanism. Fig. 10 is an end elevation of same. Fig. 11 is an end elevation of the cams and associated mechanism. Fig. 12 is a section on line 12—12 of Fig. 1, on an enlarged scale. Fig. 13 is a fragmentary elevation of 34, also on an enlarged scale. Fig. 14 is a section on line 14—14 of Fig. 7. Fig. 15 is a fragmentary sectional plan view. Fig. 16 is a front elevation of the pusher elements and associated parts. Fig. 17 is a plan view of same.

Similar numerals refer to similar parts throughout the several views.

Referring to Figs. 1 and 6, 22 and 23 are a pair of feed or folding rollers of a folding machine. Beneath these rollers are the rollers 25 and wheels 26. Rollers 25 are adapted to coöperate with the cutting wheels 26. Rollers 22, 23 and 25 are usually geared together and positively driven. Wheels 26 are provided with cutting knives and are adapted to move into and out of coöperation with the rollers 25 and are driven by frictional contact therewith. The cutting wheels 26 are mounted on brackets 27. These brackets have a transverse sliding engagement on the rail 29, secured to the stationary framework 21. There may be any number

of cutting wheels 26, depending upon the number of cuts required. In case it is desired to pack the sheet passing through rollers 22 and 23 without cutting, then wheels 26 may be omitted or the knives removed therefrom.

The transverse movement of the several blocks 28 is for the purpose of securing the desired number of cutting wheels on the machine and the desired positions of said cutting wheels for the purpose of securing the cutting of the sheet in the desired sizes and number of sections. The rollers 25 are adjustable on the shaft 33 and correspond in number and position to coöperate with the cutting wheels 26. It will be understood that ordinarily the two wheels carried by the brackets 27 at the extreme right and the extreme left of the machine, correspond to the cutting wheels 26 in coöperating with rollers 25 to feed the sheets, but are not provided with cutting knives.

Packing mechanism.—The trough for receiving the sheets comprises the bottom slats 31 and 32 and the side walls 34, and ordinarily the intermediate partitions 35. Walls 34 and partitions 35 are clamped between the two elements of the split rails 32. In case single sheets are delivered into the trough from the feed rollers without cutting, then the partitions 35 are eliminated, as shown in Figs. 4 and 5.

In Figs. 2 and 3, I show a machine adapted to cut each sheet into four sections; the trough being divided into four corresponding parts by the partitions 35. The shaft 36 is journaled in stationary boxes connected with the stationary framework. Shaft 37 has a journaled connection with the trough structure and moves therewith as hereinafter described. Referring especially to Fig. 10, it will be seen that shaft 36 is provided with a sector gear 38 coöperating with sector gear 39 which is secured to shaft 40, mounted in the stationary framework, see Figs. 1, 9 and 10, while shaft 37 is provided with sector gear 41 coöperating with sector gear 42 secured to shaft 40. Shaft 40 is provided with a bifurcated arm 43 to which is connected one end of connecting rod 44, the other end of said rod being connected with the extension 45 of the lever member 46, see Fig. 9. Extension 47 of said member is provided with a roller 48 adapted to coöperate with the cam 49. Extension 50 of said member is connected with

the spring controlled rod 51. On shaft 36 are mounted a number of hooks 52, while shaft 37 is provided with a number of hooks 53. The lever 46 is loosely journaled on the shaft 54. The pusher member 55, there being a plurality of these also, consists of a bent bar secured to yoke 56; yoke 56 being transversely adjustable on the cross bar 57. The cross bar 57 is connected at one end to member 58 which is slidably supported in brackets 59 on member 60 which is secured to the stationary framework. The other end of bar 57 is slidably supported in channeled member 102 also secured to the stationary framework. To bar 57, near each end, is connected one end of the connecting rod 61, the other end of one connecting rod 61 is adjustably secured in the slots 62 of lever 63, see Fig. 8, while the other end of 20 the other connecting rod 61 is secured to a similar slot at the lower end of lever 65, see Fig. 11. Levers 63 and 65 are both keyed to the shaft 54. The upper end of lever 65 is provided with a roller 66 adapted to operate with a cam 67. The extension 68 is connected with a spring controlled rod 69. Cams 49 and 67 are mounted on shaft 70.

Trough structure.—The slats 31 and 32 of the trough structure are provided with brackets 71 and 72. These brackets are supported on rods 73 and 74, being adjustably secured thereto by the set-screws 75. The rods 73 and 74 are secured to and supported by the members 76 and 77. These members 76 and 35 77 are adjustably mounted on the vertical posts 78 and 79. These posts 78 and 79 are provided with teeth forming a rack for cooperation with the pinions 80 and 81 mounted on shaft 82 and operated by the hand 40 wheel 83. The posts 78 and 79 are secured to the stationary framework by means of brackets 84, 85, 86 and 87 as clearly shown in Figs. 1, 2 and 3 especially.

It may be noted that the journal boxes 88 and 89 of shaft 37 are secured to the rod 74 and are movable therewith as hereinafter described.

On the slats 31 are slidably mounted the channeled castings 90, see Figs. 7 and 14; 50 said casting having an extension 91 at right angles with the channeled portion, and a rod 92 extending from said extension 91, parallel with the casting 90, and secured to the said extension 91. The rod 92 has at 55 its free end a collar 93 secured rigidly thereto. Member 94 is slidably mounted on the slat 31 and is loosely connected at its other end with rod 92, between the collar 93 and the spring 95 which surrounds the greater 60 portion of rod 92. The washer 96 is preferably provided between the spring 95 and member 94. The extension 91 is suitably apertured and is adapted to have secured thereto the face member 97, of any desired 5 dimension, by means of the bolts 98.

The operation of my device is as follows: It will be understood that the folding blade and the feed or folding rollers 22, 23 and 25 and also the shaft 70 are positively driven from any suitable source of power, and are 70 suitably geared so as to have the desired relative operation. The sheet is ordinarily folded between rollers 22 and 23 although in some cases it may go through without folding. The sheet may then be cut into 75 the desired number of sections by the cutting wheels 26 co-operating with the rollers 25, or the sheet may be fed between the wheels 26 and roller 25 without being cut when so desired, in which case the knives 80 are removable from the wheels 26. The sheet, which we have indicated by the numeral 30 in Fig. 1, when delivered by the rollers 25 and 26 falls between the outer end of the hooks 52 and 53 and the pusher members 55, ordinarily resting upon the slats 31 and 32.

From an inspection of Fig. 3, it will be noted that the lower portions of hooks 53 project slightly between the pusher members 55, and that the sheet, if it reaches the slats 31 and 32, becomes slightly corrugated at its lower edge as indicated in Fig. 3. This slight jamming of the sheet between the ends of the hooks 53 and the pusher 95 members 55 has a useful purpose in preventing any tendency of the sheets to bounce, as they would be liable to do, were they to drop freely upon the slats 31 and 32. In case by any chance the sheet is prevented by 100 the hooks 53, from reaching slats 31 and 32, while the hooks are in the closed position, it will immediately follow the downward movement of the hooks until it reaches the slats.

The operation of the several mechanisms is so timed that, after the sheet has reached the position described, the shaft 40 is slightly turned by the movement of the connecting rod 44 causing the simultaneous actuation of shafts 36 and 37 to raise the upper hooks 52 and lower the lower hooks 53 into the position shown in Figs. 6 and 9. As soon as the hooks have cleared the path of travel of the sheet the pusher members 115 55 are actuated to move the sheet 30 against the pile 100. The travel of the pusher members 55 is sufficient to move the packer members or face blocks 97 against the tension of springs 95 in the early stages of the packing. After a large number of sheets have been packed together the spring or elasticity of the pile will be sufficient to allow for this movement. The movement of the pusher members must be sufficient to carry 120 the sheet past the shoulders 101, so that the same will snap past said shoulders as indicated in Fig. 15, and engage themselves behind the shoulders as clearly shown in Figs. 3 and 15, after the pusher members have 130

been withdrawn, and the spring packers have returned the pile of sheets to the normal position in which the sheets are held firmly against blocks 101 and the hooks 52 5 and 53, so that no sheet, especially the last sheet, can slip out of position. As the sheets are added to the pile, the sliding member 90 is pushed along the rail 31 and step by step kicks the lower end of the locking member 10 94 along the rail ahead of it. This permits the gradual movement of the packing member or face block 97, as the pile of sheets is added to, but prevents its sliding away faster than is required.

15 As stated before, one of the features of this device is its adaptability for a large range of work, that is to say, it is capable of packing single sheets having an extension both vertically and horizontally correspond-

20 ing to the maximum capacity of the machine, or with a minimum vertical dimension, or with a minimum horizontal dimension. These relative dimensions may be varied at will. By the use of the cutter 25 wheels and the proper adjustment of the partitions and slats, both with respect to each other, and their common altitude with respect to the machine, the required number 30 of piles of sheets of desired size may be packed.

In Figs. 2 and 3, a machine is shown adapted to handle four piles separated by the partitions 35. Fig. 1 illustrates the machine handling sheets of a height equal to 35 approximately its capacity. It is obvious however that by changing the size of the packers or face blocks 97, and by turning the wheel 83 to elevate the structure supported on the members 76 and 77, which 40 includes the slats and the lower hook mechanism, this structure may be elevated to any desired degree to suit sheets of very much smaller vertical extension. In this connection it is to be noted that when shaft 37 is 45 raised with the trough, sector gear 42 may be pushed up shaft 40 to properly mesh with gear 41, and secured by a set screw or other suitable means not shown.

It will be observed from an inspection of 50 the drawings that the upper hook 52 is bifurcated and adapted to straddle the lower hook 53, thus permitting the parts to be brought into close proximity.

What I claim is:—

55 1. In a packing mechanism, the combination of a trough comprising a number of split slat elements, and recessed side elements, a pair of supporting rods therefor, a pair of vertical posts and horizontal bars, 60 slideable thereon as supporting means for said rods, and rack and pinion means for causing the vertical adjustment of said horizontal bars thereof.

2. In combination with folding and feeding mechanism, a packing mechanism comprising a trough having separated split slats comprising part of the bottom thereof, and removable sides and partitions, vertically adjustable supporting means for said trough elements, adjustable cutting elements comprised in the feeding mechanism, and interchangeable packer members slidably connected with the trough, as and for the purpose specified. 65

3. In a packing mechanism, the combination of a trough, means for delivering sheets thereto, oppositely disposed series of hooks, each series mounted on a rock shaft, and sector-gear mechanism connecting said rock shafts with a source of power as means for 80 rocking said shafts simultaneously to open and close the hooks.

4. In a packing mechanism, the combination of a trough and means for feeding sheets thereto, two oppositely disposed series 85 of hooks, each series mounted on a rock shaft, a vertical shaft having sector gear connection between said rock shafts, and cam means for oscillating the vertical shaft.

5. In combination with folding and feeding mechanism a packing mechanism, comprising a trough having separated split slats comprising part of the bottom thereof, and removable sides and partitions, vertically adjustable supporting means for said trough 95 elements, and adjustable cutting elements comprised in the feeding mechanism, as and for the purpose specified. 90

6. In a packing mechanism, the combination of a trough having separated split slats 100 comprising part of the bottom thereof, and removable sides and partitions, vertically adjustable supporting means for said trough elements, two oppositely disposed series of 105 hooks, means for opening and closing the same at intervals, one series of hooks mounted on the trough supporting means and vertically adjustable therewith.

7. In a packing mechanism, the combination of a trough and means for feeding 110 sheets thereto, the trough comprising separated adjustable slats forming a bottom thereof, and removable side walls or partitions connected with the slats to secure the required number of divisions for said 115 trough, supporting cross rods for the slats and a supporting frame for the cross rods, said supporting frame having vertical adjustment on stationary posts and a rack and manually operated pinion for coöperating 120 therewith to secure said vertical adjustment.

HOWARD K. KING.
